GEORGE M. BACKUS, OF OIL CITY, PENNSYLVANIA.

Letters Patent No. 105,410, dated July 19, 1870.

IMPROVEMENT IN SUCKER-ROD CONNECTIONS.

The Schedule referred to in these Letters Patent and making part of the same.

To all whom it may concern:

Be it known that I, GEORGE M. BACKUS, of Oil City, in the county of Venango and State of Pennsylvania, have invented a new and useful Improvement in Sucker-rod Connections; and I do hereby declare that the following is a full, clear, and exact description thereof, which will enable others skilled in the art to make and use the same, reference being had to the accompanying drawing forming part of this specification.

This invention relates to a new and useful improvement in mode of fastening the wooden sucker-rod to the iron ferrule of the joint of an oil-well, and consists in fixing steel springs (one or more) in the rod, and forming grooves or notches (one or more) in the ferrule, with which grooves or notches the steel springs are made to engage, as will be hereinafter more fully described.

In the accompanying drawing—

Figure 1 represents a longitudinal section, showing the rod and the ferrule connected according to my invention, the section being on the line *x x* of fig. 2.

Figure 2 is a horizontal or cross-section of fig. 1, on the line *y y*.

Similar letters of reference indicate corresponding parts.

A is the metallic ferrule, by means of which the sections of the sucker-rod are joined together.

On the inner side of this ferrule I form one or more grooves, notches, or offsets, marked *B*.

C represents the wooden sucker-rod.

D represents steel or other metallic springs, which are mortised through the rod, (one or more in number.)

The mortises through the rod allow play to the ends of the springs, as seen in the drawing.

The ends of the springs project, or their length is greater than the diameter of the rod.

The wooden rod is made to quite fill the ferrule, and, when the rod is driven into the ferrule, the ends of the springs curve upward, (the play referred to above allows of this,) but when the ends of the springs reach the grooves *B* they recoil and catch in the grooves, as seen in the drawing.

This is a cheap and most effectual method of fastening the wooden sucker-rod into the iron ferrule, for forming the joint, and its advantages over the ordinary mode must be obvious to all.

Having thus described my invention,

I claim as new and desire to secure by Letters Patent—

Fastening the sucker-rod *C* to the ferrule *A* by means of the springs *D* and grooves or notches *B*, substantially as shown and specified.

GEORGE M. BACKUS.
